FAUCET ATTACHMENT FOR BUBBLE BATH
Charles M. Roth, Berwyn, Ill.
Application August 4, 1950, Serial No. 177,729
1 Claim. (Cl. 299—107)

This invention relates to an attachment for faucets and it relates more particularly to an attachment by which a large volume of bubbles are generated in a bath tub.

The usual bath tub faucet is adapted to direct a stream of water almost perpendicularly downward into the body of water already in the tub. Under such circumstances, it has been found that the formation of bubbles, after the water is properly softened, occurs only in the area where the oncoming stream strikes the surface of the water and the bubbles which are formed remain substantially in the same area and are not distributed throughout the tub. The amount of bubbles formed by this arrangement is at a minimum because the oncoming stream of water is unable to engage the surface of the water in the tub in a manner to create greatest turbulence, the force of the oncoming stream is slowed by previous engagement with the volume of bubbles already there, and the impact of the stream with the formed bubbles causes their breakdown so as to eliminate some portion of the already formed bubbles.

An object of this invention is to produce an attachment of the type described by which the stream of water is directed on to the surface of the water already in the tub at an angle to create maximum turbulence while entrapping air in greater volume for bubble formation. The impact of the stream with the body of water at an angle causes a desirable circulation of the water in the tub so as to effect distribution and travel of the bubbles that are formed to other parts in the tub and thereby enhance the force reaction between the oncoming stream and the body of water for bubble formation.

More particularly, it is an object of this invention to provide an attachment of the type described which may be used to form a bubble bath, and it is a related object to provide a low cost attachment which may be readily shifted into position of use, and which is efficient and simple in operation.

These and other objects of this invention will herein-after appear, and for purposes of illustration, but not of limitation, an embodiment of the invention is shown in the accompanying drawing, in which—

Figure 1 is an elevational view of an attachment embodying features of this invention;

Figure 2 is an end view from the top of the attachment shown in Figure 1;

Figure 3 is an enlarged sectional elevational view taken along the line 3—3 of Figure 1, and

Figure 4 is a plan view showing the attachment in position of use on the end of a faucet, and indicating the reaction thereof when in use in a bath tub.

The principles of this invention reside in a faucet attachment having a restricted outlet portion disposed at an acute angle with the surface of the water in the tub or the like, for the purpose of directing the stream of water at high velocity into the body of water at an angle to create maximum turbulence and circulation of the water, while at the same time drawing larger volume of air into the body of water whereby bubbles are formed. If the water in the tub is properly softened with detergent or other surface-active chemicals, the bubbles that are formed remain and pile up in larger volumes than have heretofore been possible by ordinary use of a faucet.

An attachment embodying features of this invention comprises a tubular member 10, which may be formed of metal, plastic or other like rigid material, having a curvilinear end portion 11 adapted to project a stream of water (arrow 12) issuing from the nozzle 13 at the most disturbing angle for the body of water 14 in the tub. It has been found that greatest turbulence of the type described is achieved when the nozzle portion is arranged at an angle between 20 and 45 degrees, with the vertical, and preferably about 35 degrees. An angle greater than 45 degrees is undesirable because the stream of water is thrown out too far so that the force is mostly spent before it strikes the surface of the body of water in the

2

tub. Although it is not essential, best results are secured when the nozzle portion is formed to have an outlet of lesser dimension than the tube 10 in order to force the stream of water from the nozzle at greater velocity. It has also been found best to flatten the end portion of the tube, as at 11a, so that the nozzle is in the form of an elongate opening which causes the water to issue in a ribbon-like stream further to increase the area of engagement with the body of water 14.

10 The tube portion 10 is shown as being joined to the faucet 15 by an adapter 16 formed of rubber or rubber-like materials having ribs 17 about the outer wall to provide a better gripping relation for manually forcing the adapter onto the faucet or for removing same from position of use. To establish a desired gripping relation which militates against the adapter being forced off of the faucet and in order to provide for the use of the adapter with all sizes of conventional faucets, the bore through the adapter is decreased in stepwise arrangement, as illustrated by figures 18, 19 and 20. Circumferential grooves 21, having a sharp abutment 22 in the direction to resist removal of the adapter from the faucet, are circumferentially arranged throughout the bore to enhance the permanence of the assembled relation.

25 The tube 10 is secured in position of use by a frictional grip established between the end portion 23 of the tube and the outer end portion of the bore 24 which is adapted to be stretched when the tube is inserted therein. Instead, other means may be used, such as forming the end of the 30 tube with a flared portion adapted to rest upon a shoulder formed where the bore is reduced in dimension and through which the tube is inserted when in position of use. In a further alternative, the adapter and the tube may comprise a unitary assembly which may be screwed 35 or otherwise secured onto the faucet.

It will be apparent from the description that an attachment of the type described may be readily placed upon the end of a faucet so as to direct the stream of water at high velocity and at a desirable angle into the body of water in the tub, whereby maximum turbulence and bubble formation is achieved. The angular relation is adapted also to cause constant circulation of the water in the tub so that the bubbles that are formed may be distributed over the entire area. In the event that the faucet member 40 is otherwise originally disposed, the attachment should be modified so that the nozzle causes the oncoming stream to issue at the described angle for most effective reaction with the water.

It will be understood that numerous changes may be 45 made in the details of construction, arrangement and operation without departing from the spirit of the invention, especially as defined in the following claim.

I claim:

An attachment for faucets to direct a stream of water 50 into a body of water to produce maximum turbulence for foaming in which the faucet has a vertically disposed tubular nozzle comprising a rigid and unitary tubular member of resilient friction material having a vertically disposed portion with interconnected conically shaped bores of decreasing dimension at one end for telescoping onto the nozzle for attachment and a tubular member extending from the other end having an end portion turned at an angle from 20—45 degrees with the vertical for directing the stream of water issuing therefrom at a corresponding angle into a body of water located therewith 55 beneath with the end portion of the tubular member being flattened substantially uniformly throughout a length thereof for channeling the stream to effect issuance thereof as a ribbon.
